SPECIFICATION forming part of Design No. 23,871, dated December 11, 1894.

Application filed August 13, 1894. Serial No. 520,225. Term of patent 14 years.

To all whom it may concern:

Be it known that I, FREDERICK R. CORNWALL, a citizen of the United States, residing in the city of St. Louis, State of Missouri, have 5 invented and produced a new and original Design for Glass Jars, of which the following is a full, clear, and exact description, reference being had to the accompanying drawing, wherein the figure represents a side eleva- 10 tional view, partly in section, of a jar orna- mented and shaped according to my new design.

In the drawing, A represents the body of the jar, which is cylindrical in shape, the side 15 walls thereof being gently bulged and tapered

downwardly toward the bottom, at which point they are turned in to meet the bottom, which is slightly elevated. Near the top of the jar is a rounded annulus B, and, above said annulus, are rounded screw-threads C. 2c

What I claim is—

The design for a glass jar, substantially as herein shown and described.

In testimony whereof I hereunto affix my signature, in presence of two witnesses, this 25 24th day of July, 1894.

FREDERICK R. CORNWALL.
